CLAIM

The ornamental design for a remote controller for electronic appliances having wheel-like buttons, substantially as shown and described.

DESCRIPTION

FIG. 1 is a left perspective view of the present design for a remote controller for electronic appliances having wheel-like buttons;

FIG. 2 is a front view;

FIG. 3 is a back view;

FIG. 4 is a left side view;

FIG. 5 is a right side view;

FIG. 6 is a bottom view; and,

FIG. 7 is a top view thereof.

The broken line showing is included for the purpose of illustrating portions of the article and forms no part of the claimed design.
